CLAIM

The ornamental design for a hair styler, as shown and described.

DESCRIPTION

FIG. 1 is a top plan view of a hair styler showing our new design;

FIG. 2 is a right side elevational view thereof;

FIG. 3 is a bottom plan view thereof on a reduced scale;

FIG. 4 is a left side elevational view thereof;

FIG. 5 is a front elevational view thereof; and

FIG. 6 is a rear elevational view thereof.

The cord is shown only partially for ease of illustration.
